BAG EMPTYING DEVICE

Raymond B. Small, New Rochelle, N. Y.

Application December 23, 1938, Serial No. 247,522

8 Claims. (Cl. 220—41)

The invention relates to a bag emptying device for vacuum cleaners.

The object of the present invention is to provide, for vacuum cleaner bags, an emptying device having a closure slidably mounted on the vacuum bag and movable to and from an emptying opening therein to cover and uncover such opening and having a limited flexibility to enable it, when open, to sag to a limited extent sufficient to clear the bag and at the same time possessing sufficient stability and integrity to maintain it out of engagement with the floor, so that it will not be necessary to connect or attach the outer end of the closure to the bag to accomplish this purpose.

It is also an object of the invention to provide a device of this character having a closure comprising a single sheet of yieldable material of greater thickness than the corresponding dimension of the guides in which the closure slides, whereby the closure when moved to its closed position will be compressed by the guides and maintained in dust-proof contact with the bag, thereby obviating the necessity of padding the bag around the emptying opening or providing any other form of packing for rendering the closure dust-tight.

It is also an object of the invention to provide the slidable closure with means arranged to engage the closure guides for limiting the closing movement of the closure and adapted also to compress the end portion of the closure tightly against the bag for insuring a dust-tight connection thereto when the closure is in its closed position.

It is also an object of the invention to provide a bag emptying device having a closure with the adjacent characteristics capable of being operated by a dirt cup or receptacle slidable in the closure guides and movable into registering relation with the emptying opening of the vacuum bag as the closure is moved therefrom and adapted to return the closure to its closed position as the dirt cup is withdrawn from beneath the bag emptying opening, so that the bag emptying opening will be covered at all times either by the closure or the dirt cup or by portions of both of the same and escape of dust into the surrounding atmosphere effectually prevented.

With the above and other objects in view, the invention consists in the construction and novel combination and arrangement of parts herein-after fully described, illustrated in the accompanying drawings and pointed out in the claims hereto appended, it being understood that various

changes in the form, proportions and minor details of construction, within the scope of the claims, may be resorted to without departing from the spirit or sacrificing any of the advantages of the invention.

5

In the drawings:

Figure 1 is a perspective view of a vacuum cleaner provided with a bag emptying device constructed in accordance with this invention, the dirt cup being removed and the closure being shown in its closed position.

Figure 2 is an enlarged perspective view of the bag emptying device, the parts being arranged as shown in Figure 1 without the dirt cup.

Figure 3 is an enlarged longitudinal sectional view taken on the line 3—3 of Figure 2.

Figure 4 is a transverse sectional view taken on the line 4—4 of Figure 2.

Figure 5 is a similar view taken on the line 5—5 of Figure 2.

Figure 6 is an enlarged longitudinal sectional view, the dust cup being in position for moving the closure to open position.

Figure 7 is a similar view, the closure being open and the dust cup being located beneath the bag emptying opening.

Figure 8 is a transverse sectional view taken on the line 8—8 of Figure 7.

In the accompanying drawings in which is illustrated the preferred embodiment of the invention, the bag emptying device, which may be applied to any vacuum cleaner having a dust receiving bag, comprises in its construction a slid-
able closure 1 constructed of soft, yieldable, com-
pressible rubber or similar material and consists 35
of a single sheet of rubber or other material hav-
ing similar characteristics reinforced by a sheet
2 of woven wire embedded in the relatively soft,
flexible, yieldable and compressible sheet 1 and
adapted to stiffen the same transversely and to 40
limit the flexibility of the closure 1 longitudinally
in the direction of its sliding movement, so
that, when the closure is moved by a dirt cup 3
or an analogous receptacle from the closed po-
sition illustrated in Figure 6 of the drawings to 45
the open position shown in Figure 7, it will sag
slightly and sufficiently to prevent it from engag-
ing the bag and will have sufficient stability and
integrity to support itself in an elevated position
above the floor when the dirt cup is arranged 50
upon the same for emptying the contents of the
bag 4 of the vacuum cleaner into the dirt cup.
The closure 1, which has continuous, smooth, un-
broken upper and lower surfaces, is slidably
mounted in guides 5 which are secured by bolts 55

6 or other suitable fastening devices to opposite sides of a rigid rectangular frame 7 sewed into the vacuum bag 4 and framing a rectangular emptying opening 8, as clearly illustrated in Figures 4 and 5 of the drawings. The frame 7 is constructed of metal or other suitable material and the guides 5 are preferably stamped or otherwise formed from sheet metal or other suitable material. The guides 5 have angular bends extending longitudinally of the guides and forming guiding flanges 9 which cooperate with the frame 7 to form guide grooves for the reception of the side edges of the slideable closure 1.

The relatively soft, yieldable material of the slideable closure is adapted to be compressed by the guides when the closure is moved along the guides to its closed position and, in order to effect a dust-tight contact with the bag, the closure is made of a thickness greater than the corresponding dimension of the guides, so that the marginal side portions of the closure will be compressed by the guides as illustrated in Figures 4 and 5 of the drawings. This will effectually prevent the escape of dust at the side portions of the closure and will also operate to maintain the end portions of the closure in tight engagement with the bag at the transverse portions of the rigid frame 7. The closure may be of any desired color to harmonize with the finish of the vacuum cleaner to which the bag emptying device may be applied. The guides 5 are beveled at 10 at the ends of the guide flanges 9 to facilitate guiding the dirt cup and the closure into the spaced guides 5. The closure is provided with transverse end bars 11 and 12 arranged on the exterior of the closure and secured to the same by suitable fastening devices 13 and 14 which pierce the end bars and the closure, but any other suitable fastening means may, of course, be provided and the said end bars 11 and 12 may be constructed of sheet metal or any other suitable material. The end bar 11 has its outer marginal portion bent into an approximately U-shaped catch 15, which is engaged by an approximately L-shaped flange 16, which forms a catch or cooperating member for detachably connecting or interlocking the dirt cup with one end of the closure, whereby the closure may be moved from its closed position to its open position and returned from the open position to the closed position by the dirt cup 3 which is provided with a suitable handle 17 to enable it to be conveniently operated. The L-shaped flange or catch 16 and the U-shaped catch 15 enable the dirt cup to be readily connected with and disconnected from the closure when the closure is in its closed position, but as soon as the dirt cup, which is provided with side flanges 19 to engage the guides 5, is moved between the guides and the closure is partly or fully open, the guides will prevent the dirt cup from being detached from the slideable closure, as it will be impossible for the dirt cup to be arranged at the angle necessary to carry the L-shaped flange 16 out of engagement with the catch 15. As soon as the dirt cup is moved between the beveled portions of the guides, it may be readily disconnected from the closure as the beveled portions of the guides will not interfere with the necessary movement of the dirt cup to effect this disengagement of the L-shaped flange 16 from the U-shaped catch 15.

The end bar 12 at the other end of the closure is provided with terminal tongues 20 which are bent inwardly towards the dust bag 4, as clearly illustrated in Figure 2 of the drawings, to arrange

them in proper position for positively engaging the guides and also to cause the tongues to compress the adjacent portion of the closure and maintain the same in dust-tight contact with the bag. Also the outer marginal portion 21 of the end bar 12 is slightly deflected by a longitudinal bend for forcing the marginal portion of the closure inwardly into dust-tight engagement with the bag. The tongues 20 are of a width less than that of the end bar 12 and are formed by recessing or cutting away the end bar at the terminals thereof and the marginal portion of the end bar 12 lies between the guide bars when the closure 1 is in its closed position.

One of the end bars is provided with a recess 22, which, when the closure is in its closed position, is adapted to be engaged by a slideable latch 23 consisting of a plate provided with spaced slots 24, through which pass headed fastening devices 25 which slidably secure the latch to the exterior 20 of the closure. The latch is disposed transversely of the closure adjacent to one edge thereof and its inner end is bent outwardly to provide a finger piece 26 to enable the slideable latch to be readily manipulated in moving it into and out 25 of engagement with the recess.

The dirt cup 3, which may be made of sheet metal or any other suitable material, is preferably rectangular and is designed to be provided with a contracted upper portion 27 to conform 30 to the size of the emptying opening of the bag and at the same time to enable the dirt cup to be made of the desired capacity. The dirt cup is provided at one end with a downwardly extending L-shaped flange 16 and provided at its other 35 end with an upwardly extending L-shaped flange 21, which forms a stop for engaging the adjacent transverse portion of the frame 7 to limit the sliding movement of the dirt cup and the cover actuated by the same. The stop flange 40 21 may, however, be arranged to engage the ends of the guides to limit such movement, but any suitable stop means may be provided.

When the dirt cup is applied to the vacuum cleaner bag 4 as illustrated in Figure 7 of the drawings, it is lowered to a horizontal position to rest upon the floor and the upper end of the bag 4 may be detached from the handle of the vacuum cleaner, but the bag may be emptied without detaching it from the handle. After the bag has been emptied, the closure is returned to its closed position by the dirt cup and the latter is then disengaged from the closure. The bag emptying device will enable a vacuum cleaner 45 dust bag to be emptied of its contents without permitting any dust to escape into the surrounding atmosphere and, in the opening movement of the closure, any dust on the inner surface of the closure will be swept into the dirt cup as the 50 smooth surface of the closure passes beneath the rigid frame.

In the use of the vacuum cleaner, the closure is maintained in position against opening incident to the frictional resistance which would 65 be encountered in any movement of the cover with relation to the guides due to the compressive action on the longitudinal edges of the closure by the guides, obviating the use of any holding means or latch to maintain the closure in normal 70 position over the emptying aperture. The nature of the material of which the closure is composed, as hereinbefore described, is such as to tend to seal the closure against movement incident to any internal pressure within the bag. 75

What is claimed is:

1. A bag emptying device for vacuum cleaners including a bag having an aperture for emptying purposes, a slidable cover comprising a single sheet of relatively soft, yieldable, flexible material presenting a smooth, continuous, unbroken surface to the bag and adapted to be held in compressed dust-proof contact with the same thereby eliminating packing, and a sheet of wire mesh 10 material embedded in the sheet of flexible material and stiffening the same transversely and limiting the flexibility of the closure longitudinally in the direction of its sliding movement whereby the flexible closure will flex sufficiently to clear 15 the bag and will have sufficient stability to hold itself in an elevated position out of contact with the floor when the closure is moved to open position.
2. A bag emptying device for vacuum cleaners 20 including a bag having an aperture for emptying purposes, a rigid frame surrounding the aperture and secured to the bag, spaced guides joined to the frame, and a closure slidable in the guides and comprising a single sheet of relatively soft, 25 yieldable, flexible, compressible material of greater thickness than the corresponding dimension of the guides, whereby when the cover is moved into closing position it will be compressed by the guides and will form a dust-tight connection with 30 the bag without additional packing.
3. A bag emptying device for vacuum cleaners including a bag having an aperture for emptying purposes, a rigid frame surrounding the aperture and secured to the bag, spaced guides 35 joined to the frame, a closure slidable in the guides and comprising a single sheet of relatively soft, yieldable, flexible, compressible material of greater thickness than the corresponding dimension of the guides, whereby when the 40 cover is moved into closing position it will be compressed by the guides and will form a dust-tight connection with the bag without additional packing, and a sheet of woven wire embedded within the sheet of yieldable material and stiffening the same transversely and limiting the 45 flexibility of the yieldable sheet longitudinally in the direction of the sliding movement of the closure adapted to permit a sufficient flexing of the closure to prevent contact with the bag when the 50 closure is in its open position, the wire mesh imparting sufficient stability to the flexible sheet to enable the same to maintain itself out of contact with the floor when the closure is moved to open position.
4. A bag emptying device for vacuum cleaners 55 including a bag having an aperture for emptying purposes, a rigid frame secured to the bag and surrounding the aperture, spaced guides joined to the frame, a closure slidable in the guides comprising a single sheet of relatively soft, 60 yieldable, compressible material, and a transverse end bar secured to the exterior of the clo-

sure and provided with terminal tongues arranged to engage said guides to limit the closing movement of the closure and flexed inwardly in the direction of the bag for compressing the yieldable material in dust-tight engagement with the bag. 5

5. A bag emptying device for vacuum cleaners including a bag having an aperture for emptying purposes, a rigid frame secured to the bag and surrounding the aperture, spaced guides joined to the frame, a closure slidable in the guides comprising a single sheet of relatively soft, yieldable, compressible material, and a transverse end bar secured to the exterior of the closure and provided with terminal tongues arranged to engage said guides to limit the closing movement of the closure and flexed inwardly in the direction of the bag for compressing the yieldable material in dust-tight engagement with the bag, said end bar also having its outer marginal portion flexed inwardly for compressing and holding the closure in tight engagement with the bag. 10 15 20

6. A bag emptying device for vacuum cleaners including a bag having an aperture for emptying purposes, spaced guides located at opposite sides 25 of the aperture, one of the guides being provided at its inner edge with a recess, a closure slidable in the guides for covering and uncovering the aperture, and a latch slidably mounted on the closure and arranged to engage said recess for locking the closure in its closed position. 30

7. A bag emptying device for vacuum cleaners including a bag having an aperture for emptying purposes, a frame secured to the bag and surrounding the aperture, spaced guides secured to the frame, a closure slidable in the guides and normally closing said aperture and including a sheet of relatively soft, yieldable, compressible material of a thickness slightly greater than the corresponding dimension of the guides so as to provide for a relatively tight, sliding, frictional fit of the longitudinal edges of the closure in said guides to thereby maintain the closure normally closed. 35 40 45

8. A bag emptying device for vacuum cleaners having an aperture for emptying purposes, a frame secured to the bag and surrounding the aperture, spaced guides secured to the frame, a closure slidable in the guides and normally closing said aperture and including a sheet of relatively soft yieldable, compressible material of a thickness slightly greater than the corresponding dimension of the guides so as to provide for a relatively tight sliding frictional fit of the longitudinal edges of the closure in the guides to thereby maintain the closure normally closed, and a transverse bar carried by the flexible closure and provided with terminal projections arranged to engage said guides to limit the closing movement of the closure. 50 55 60
